US00D508611S

(12) **United States Design Patent** (10) Patent No.: **US D508,611 S**
(45) Date of Patent: **** Aug. 23, 2005**

(54) **SURFACE PATTERN FOR SHEET GOODS**

(75) Inventor: **Rolf Kuhnert**, Heilbronn (DE)

(73) Assignee: **Lidl Stiftung & Co. KG**, Neckarsulm (DE)

(**) Term: **14 Years**

(21) Appl. No.: **29/211,132**

(22) Filed: **Aug. 11, 2004**

(30) **Foreign Application Priority Data**

Mar. 15, 2004 (DE) 4 04 01 761

(51) LOC (8) Cl. **05-06**

(52) U.S. Cl. **D5/26**

(57) **CLAIM**

The ornamental design for a surface pattern for sheet goods, as shown and described.

DESCRIPTION

The sole FIGURE is a view of a surface pattern for sheet goods. The broken line boundary of the sheet goods are for illustrative purposes only and form no part of the claimed invention.

1 Claim, 1 Drawing Sheet

U.S. Patent

Aug. 23, 2005

US D508,611 S
